UNITED STATES PATENT OFFICE.

JASPER P. FELL AND EDGAR C. GREGG, OF WHEELING, MISSOURI.

HAY-STACKER.

SPECIFICATION forming part of Letters Patent No. 270,043, dated January 2, 1883.

Application filed October 6, 1882. (No model.)

To all whom it may concern:

Be it known that we, JASPER P. FELL and EDGAR C. GREGG, of Wheeling, in the county of Livingston and State of Missouri, have invented certain new and useful Improvements in Hay-Stackers; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view, Fig. 2 is a vertical sectional view, and Fig. 3 is a rear view, of our improved hay-stacker.

The same or corresponding parts in the several figures are denoted by the same letters of reference.

This invention relates to hay-stackers; and it consists in certain improvements in the construction of the same, which will be hereinafter fully described, and particularly pointed out in the claims.

In the drawings hereto annexed, A represents the horizontal base-frame, which, if desired, may be mounted upon wheels, in order to enable the device to be conveniently moved from place to place.

B B are uprights mounted at the rear end of frame A, and supporting the upper ends of the inclined track-beams C C, the lower ends of which are secured to the front end of frame A. Extension-pieces D D are hinged or jointed to the lower ends of the track-beams C by straps E. Said extension-pieces, when the device is in use, reach to the ground. When not in use they may be folded up upon the main track-beams, so as not to interfere with the moving of the machine.

F is the carrier, which consists of a set or series of teeth or fingers, G, connected by transverse bars or braces H. The carrier is provided with two rearwardly-extending arms, I I—one on each side of the base-frame and inclined track—and the rear ends of which are pivoted to the lower front ends of short arms J, pivoted at the rear corners of the base-frame.

K K are teeth pivoted to the rear ends of the teeth G of the carrier, and constituting, together with a transverse bar, L, by which they are connected, the compressing-frame M.

N N are arms pivoted to the sides of two of the teeth K, and having their rear ends pivoted to the arms J in rear of the points at which the arms I, above described, are pivoted to the said arms J. The arms I I are connected by a transverse rod, O, upon which are mounted a pair of flanged wheels or rollers, P P, traveling upon the inclined track-beams. The rollers P have grooves Q to receive the hoisting-tackle, as will be presently described.

R R represent pulleys mounted in brackets S at the upper ends of the track-beams C. The uprights B B, supporting said track-beams, are connected by a cap-piece or brace, T, and by diagonal braces U, at the lower ends of which are brackets V, in which pulleys W are mounted.

The hoisting-ropes X X are made fast at the upper ends of the track-beams C. They pass from thence over the wheels or rollers P, where they are received in the grooves Q, then over the pulleys R at the upper ends of the track-beams, and finally down over the pulleys W, after which they are connected in any suitable manner to enable the draft to be properly applied.

The operation of our invention will be readily understood. When the carrier is lowered to the ground the load is deposited upon it by the rake or gatherer, or in any suitable manner. Draft being then applied to the hoisting-ropes, the carrier is elevated upon the inclined track, where it is gradually tilted by the pivoted arms I J. The latter and the arms N also serve to throw the compressing-frame M forward, thus compressing the load and holding it securely while being elevated. When the summit of the track is reached the arms J, which have been moved in a downward and rearward direction by the arms I of the carrier, are again raised with the latter, thus tilting the compressing-frame downwardly and permitting the load to slide off upon the stack. When the draft upon the hoisting-ropes is released the weight of the carrier causes it to return to its original position.

We claim and desire to secure by Letters Patent of the United States—

1. In a hay-stacker, the combination, with the base-frame and the inclined track-frame, of the arms J, pivoted at the rear corners of the base-frame, the rearwardly-extending carrier-arms

I, pivoted to the lower ends of said arms J, the compressing-frame M, pivoted to the carrier, the arms N, connecting said frame M with the pivoted arms J, and the rod O, connecting the arms I, and having rollers P, as set forth.

2. As an improvement in hay-stackers, the combination and arrangement, as described, of the base-frame, the inclined track, having hinged extensions D, the carrier F, arms I, the pivoted arms J, the compressing-frame M, pivoted connecting arms N, rod O, flanged rollers P, provided with grooves Q, the pulleys

R and W, and the hoisting-ropes X, all constructed and operating substantially as set forth.

In testimony that we claim the foregoing as our own we have hereunto affixed our signatures in presence of two witnesses.

JASPER P. FELL.
EDGAR C. GREGG.
